M. HUFFMAN

STEAM BOILER CLEAN-OUT DEVICE

Filed Dec. 6, 1921

Patented Feb. 13, 1923.

1,445,592

UNITED STATES PATENT OFFICE.

MIKE HUFFMAN, OF DES MOINES, IOWA.

STEAM-BOILER CLEAN-OUT DEVICE.

Application filed December 6, 1921. Serial No. 520,312.

To all whom it may concern:

Be it known that I, MIKE HUFFMAN, a citizen of the United States, and a resident of Des Moines, in the county of Polk and 5 State of Iowa, have invented a certain new and useful Steam-Boiler Clean-Out Device, of which the following is a specification.

My invention relates to that class of steam boiler clean-out devices in which there is inserted 10 slightly above the bottom of the boiler on its interior a pipe having openings therein and leading to a point of discharge exterior to the boiler, and also a means whereby the discharge end of the pipe 15 may be opened so that the steam pressure within the boiler will cause the mud, sediment and scale within the boiler to be blown out through said openings.

My object is to provide a device of the 20 class described of simple, durable and inexpensive construction and particularly to provide such devices which may be readily, quickly and easily installed in a boiler and after installation will be firmly and securely 25 supported in its position.

A further object is to provide improved 30 means for protecting that part of the discharge pipe which extends through the boiler and the fire box and through the rear wall of the furnace from being burnt out by the excessive heat at the rear of the fire box.

My invention consists in the construction, 35 arrangement and combination of the various parts of the device, whereby the objects contemplated are attained, as hereinafter more fully set forth, pointed out in my claims, and illustrated in the accompanying drawings, in which:

40 Figure 1 shows a vertical center sectional view of a boiler of the return flue type having my improved clean-out device applied thereto.

Figure 2 shows a central longitudinal sectional view of the clean-out pipe detached.

45 Figures 3 shows a detail sectional view on the line 3—3 of Figure 1, and

Figure 4 shows a detail sectional view on the line 4—4 of Figure 1.

50 Referring to the accompanying drawings I have used the reference numeral 10 to indicate generally a steam boiler of the return flue type. This boiler is provided at its front near its bottom with a hand hole 11. The rear furnace wall 12 is spaced apart from the rear of the boiler and the even flame from the fire

passes upwardly between the rear of the boiler and the rear wall to enter the return flues of the boiler.

My improved boiler clean-out device comprises a stationary pipe 13 having a series 60 of slots 14 at its bottom extending throughout its length. This stationary pipe has rotatively mounted on its interior a pipe 15 which is provided with slots 16 arranged spirally, as shown in Figure 2, so that when the inner pipe is rotated these slots 16 will successively coincide with the slots 14 and at other times will be out of line with the slots 14. I preferably provide on the stationary 65 outer pipe 13 a series of legs or supports 17 to hold the outer pipe properly spaced from the bottom of the boiler, as shown in Figure 70 4. I also preferably provide on the stationary outer pipe 13 a deflecting hood 18 supported 75 above the pipe and having its edges extended downwardly and outwardly to stand in position slightly spaced from the bottom of the boiler and thereby direct the currents of water so that they will strike 80 upon the bottom of the boiler and tend to remove any mud or sediment thereon when passing toward the discharge openings of the clean-out pipes.

For the purpose of applying these clean- 85 out pipes to a boiler and firmly and accurately securing them in position when applied, I have provided a supporting and coupling device comprising a body portion 19 preferably made of cast steel and formed 90 hollow and provided at one end with an externally screw threaded tubular extension 20, which extension has at its ends beyond the screw thread a series of angular lugs 21 with spaces between them. At the rear of the 95 body portion 19 the device is screw threaded internally to receive the pipe 22 and on its outer surface is a series of outwardly projecting lugs 23 spaced apart from each other, and on the outer or rear end of the 100 device 23 is an indicating mark 24, preferably formed by having a raised lug cast in the material. The stationary pipe 13 is provided at its rear end with lugs and spaces 25 designed to fit into and coact with the lugs 105 21, as shown in Figure 1, and on the forward end of the inner pipe 15 is a screw cap 26 designed when screwed into position to hold the inner pipe against forward movement and close the end of the outer pipe.

110 The pipe 22 is extended rearwardly through the rear wall of a furnace and is

provided at its rear end with a discharge branch 27 and a valve controlled by the hand wheel 28 for opening and closing the discharge end of the pipe 22.

5 Mounted in and supported by the rear wall 12 is a cooling and protecting tube 29 which stands spaced apart from the pipe 22 and which is supported at its forward end on the lugs 23. The forward end of this tube 29 is 10 open and stands only slightly spaced apart from the rear of the boiler.

In practical operation and assuming that it is desired to apply one of my improved 15 clean-out devices to a boiler, I first drill an opening at the rear of the boiler and provide it with an internal screw thread. I then insert the supporting and coupling device in this screw threaded opening and screw it in very tightly and until the indicating mark 24 is directly at the top. I then 20 insert through the hand hole 11 at the front of the boiler the pipes 13 and 15 and move them rearwardly until the lugs 25 of the outer pipe 13 fit into the lugs 21 of the part 25 19. This will insure that the slots 14 are directly at the bottom of the pipe 13. When 30 this has been done the inner pipe 15 will project through the part 19 and I then insert a rod 30 in the rear end of the pipe 15 and fix it firmly in position by means of a pin 31, and this rod extends rearwardly through the pipe 22 and is attached to the hand wheel 32 at the rear of the pipe 22 thus 35 firmly holding the pipes 13 and 15 against forward movement and also providing means whereby the inner pipe 15 may be conveniently and easily rotated.

After this has been done the pipe 29 may 40 be placed in position and obviously when the furnace is in operation cool air will be drawn in through the rear end of the pipe 29 and surround the pipe 22 and the part 19 and be discharged at the forward end adjacent to the rear of the boiler, thus cooling 45 the parts 19 and 22 preventing them from being burnt out. The cool air will also prevent the pipe 29 from being burnt out.

After the device has been installed as described, the operator first opens the blow-off 50 valve 28 and then rotates the inner pipe 15 by means of the hand wheel 32 thus successively bringing the slots 14 and 16 into alinement with each other and removing the mud, sediment and scale from the boiler at points 55 adjacent to said slots as they are successively brought into alinement.

I claim as my invention:

1. In a device of the class described, in 60 combination with a steam boiler of a supporting and coupling device designed to be permanently fixed in the rear wall of a boiler and provided at its forward end on the interior of the boiler with projecting lugs, two pipes, one within the other, designed to be inserted in the bottom of the

boiler and being provided with openings that may be brought into alinement with each other, one of said pipes being provided with notches to receive said lugs and the other of said pipes being capable of rotation relative to the first, a pipe connected to the supporting and coupling device at the rear end, and means extending through the said rod and connected to the rotatable one of said pipes for holding said rotatable pipe rearwardly and for providing means whereby the said rotatable pipe may be turned, for the purposes stated. 70 75

2. In a device of the class described, in combination of a steam boiler of a supporting and coupling device comprising a screw threaded extension at one end designed to be screwed into an opening in the rear of the boiler and also being provided in front of the screw thread with lugs, said device 80 having at its rear an indicating mark to visibly indicate to the operator the position of the lugs on the interior of the boiler, two pipes, one within the other, the inner one being provided with notches to receive the 85 lugs on the supporting and coupling device, both pipes being provided with openings which may be made to coincide with each other upon the rotation of the inner pipe, the supporting and coupling device being 90 also provided with outwardly projecting lugs on the exterior, a pipe screwed into the interior of the supporting and coupling device and extending rearwardly therefrom to a point beyond the end of the furnace, a discharge pipe communicating with the rear of the latter mentioned pipe, and a blow-off valve 95 therein, a rod fixed to the rear end of the inner rotatable pipe and extending to a point in the rear of the furnace, means for rotating said rod and for holding it against forward movement, for the purposes 100 stated. 105

3. In a device of the class described, in combination of a steam boiler of a supporting and coupling device comprising a screw threaded extension at one end designed to be screwed into an opening in the rear of the boiler and also being provided in front of the screw thread with lugs, said device 110 having at its rear an indicating mark to visibly indicate to the operator the position of the lugs on the interior of the boiler, two pipes, one within the other, the inner one being provided with notches to receive the 115 lugs on the supporting and coupling device, both pipes being provided with openings which may be made to coincide with each other upon the rotation of the inner pipe, the supporting and coupling device being 120 also provided with outwardly projecting lugs on the exterior, a pipe screwed into the interior of the supporting and coupling device and extending rearwardly therefrom to a point beyond the end of the furnace, a discharge 125 pipe 130

charge pipe communicating with the rear of the latter mentioned pipe, and a blow-off valve therein, a rod fixed to the rear end of the inner rotatable pipe and extending to a point in the rear of the furnace, means for rotating said rod and for holding it against forward movement, and a cooling pipe inserted through the rear wall of a furnace

open at both ends and supported at its inner end upon the lugs at the rear of the supporting and coupling device and having its inner end slightly spaced from the rear of the boiler, for the purposes stated.

Des Moines, Iowa, October 26, 1921.

MIKE HUFFMAN.
